PERSONALIZED PICTURE COMPACT

Viola R. Thomasello, Detroit, Mich.

Application October 31, 1956, Serial No. 43,606

Term of patent 14 years

(Cl. D86—10)

Fig. 1

Fig. 2

Fig. 3

Fig. 4

Fig. 5

Fig. 1 is a perspective view of my design for a personalized picture compact, shown in the open position;

Fig. 2 is a top plan view of the compact shown closed, the dotted line showing being for illustrative purposes only;

Fig. 3 is a bottom plan view thereof;

Fig. 4 is a rear elevational view; and

Fig. 5 is an end elevational view.

I claim:

The ornamental design for a personalized picture compact, substantially as shown and described.
